UNITED STATES PATENT OFFICE.

ERNEST WALTER BRUDENELL GILL AND ROBERT HOPE DONALDSON, OF OXFORD, ENGLAND; SAID GILL ASSIGNOR TO RADIO CORPORATION OF AMERICA, A CORPORATION OF DELAWARE.

THERMIONIC FREQUENCY CHANGING OR MODULATING DEVICE.

Application filed February 24, 1928, Serial No. 256,664, and in Great Britain February 18, 1927.

An application has been filed in England, Feb. 18, 1927, which embraces the invention herein described.

This invention relates to thermionic frequency changing or modulating devices, and is particularly suitable for use in wireless telegraphy and telephony.

In the specification of British Patent No. 252,079, May 18, 1926, was described a valve such that when its anode is maintained at a positive potential with respect to the cathode while a potential slightly positive or slightly negative with respect to the cathode is applied to the outer grid the inner grid being maintained as a positive potential a critical point can be found at which an increase in inner grid potential produces a decrease in inner grid current and conversely, a decrease in inner grid voltage would cause an increase in inner grid current. This characteristic has, by the inventor and by the prior art been termed as a negative resistance characteristic.

It has also been found, as pointed out hereinafter, and in the above referred to specification that under suitable conditions, the amplification capable of being obtained with valves so constructed is extremely high. The present invention utilizes such a negative resistance four-electrode valve in such a manner as to derive therefrom, the benefits of the high amplification of the valve and also of its negative resistance characteristics which inherently adapt it to generation of oscillations.

According to the present invention a thermionic frequency changing or modulating device comprises a "negative resistance" four-electrode valve as described above, means for applying to the input circuit of the said valve a modulating frequency or frequency to be changed, and which itself may be modulated by signals, and means for maintaining the output circuit of said valve in oscillation at a frequency substantially different from the first mentioned frequency whereby the amplitude of the oscillations is controlled in accordance with the said first mentioned frequency.

The invention is illustrated in the drawings accompanying the provisional specification, in which,

Figure 1 is a circuit diagram and

Figure 2 a graphic representation of results obtainable with the invention.

55

If the incoming oscillation is of shorter wave length than the local oscillation, the variation in amplitude of the local oscillations is of the same order as the incoming oscillations. If the incoming oscillation is of longer wave length, then the variations of amplitude in the local oscillator are in general much larger than in the incoming wave.

The local oscillation should differ widely in wave length from the incoming oscillations or else forced vibrations may occur. The local oscillations are maintained by negative resistance effects on the inner grid of the four-electrode valve as pointed out above and in the British specification referred to, the degree of negative resistance being controlled by the potential applied to the outer grid for a particular value of filament emission.

75

If the incoming wave is much longer than the local wave, there will be many oscillations of the local wave for a half wave of the incoming oscillations, and hence the said local waves will be enormously magnified for one half wave and enormously reduced for the next half wave. If, on the other hand, the incoming wave is shorter than the local there is only one oscillation of the local wave for several incoming oscillations. The amplitude of the local wave takes up in effect a mean value dependent on the curvature of the inner grid oscillation potential—outer grid potential curve, as shown in Figure 2. In practice the voltage variation in the latter case of the local waves is generally of the same order as the voltage variation of the incoming waves.

80

According to the present invention a thermionic frequency changing or modulating device comprises a "negative resistance" four-electrode valve as described above, means for applying to the input circuit of the said valve a modulating frequency or frequency to be changed, and which itself may be modulated by signals, and means for maintaining the output circuit of said valve in oscillation at a frequency substantially different from the first mentioned frequency whereby the amplitude of the oscillations is controlled in accordance with the said first mentioned frequency.

Referring to Figure 1, which shows in circuit diagram form one way of carrying out the invention, 1 is the receiving aerial to which is coupled, preferably variably, an oscillatory circuit 2, connected between the outer grid 10 and the cathode 13, of a four-electrode valve 3, of the kind more fully described above and in the prior British Patent No. 252,079, May 18, 1926. The plate 14 of the valve is connected through a reaction coil, variably coupled to the oscillatory circuit 2, a

100

battery 4 and a potentiometer 5 to the cathode 13. The inner grid 11 of the valve 3 is connected through an oscillatory circuit 6 and a battery 15 to the cathode. The reaction coil, aerial and oscillatory circuit 2 are tuned to the frequency to be received, e. g. a frequency corresponding to a wave length of 60 metres, while the oscillatory circuit 6 is tuned to the lower frequency, e. g. a frequency 10 corresponding to a wave length of 15000 metres. The circuit 6 is variably coupled to the input side of a known amplifier, which is permanently tuned to the lower frequency and comprises two valves 7, 8 the output from 15 the same amplifier being rectified by means of a valve 9. The four-electrode valve and the batteries associated therewith are so adjusted that the outer grid 10 is at approximately the same potential as the cathode 13, 20 the inner grid 11 and the plate 14 being maintained at a positive potential, say, 20 volts in relation thereto. Under these conditions, as is set forth above and in the said prior British Patent No. 252,079, May 18, 1926, for 25 a particular cathode emission the inner grid shows a "negative" resistance and the oscillatory circuit 6 will therefore be maintained in oscillation at its own wave length. The degree of negative resistance is critically dependent upon the outer grid potential, a very 30 small change in this potential resulting in a very large change in the amplitude of the oscillations in the circuit 6. The negative resistance effects can only be obtained over a 35 small range of outer grid potential, the relation between the outer grid potential and amplitude of oscillation within this range following a curve generally as shown in Figure 2. A potentiometer may be employed to 40 adjust the outer grid to operate at either of the points A or B of the curve shown in Figure 2.

The negative resistance effect is also dependent on the magnitude of the plate potential for a given potential on the outer grid, 45 and the plate potential may conveniently be adjusted by the potentiometer 5, which is employed to adjust the valve so that it is working at the required point corresponding to A or B of the curve.

In a modification the reaction coil in the plate circuit of the four-electrode valve is dispensed with, the said plate being connected to the same battery as is the inner grid.

55 In a further modification, suitable for receiving unmodulated continuous waves, an independent heterodyne is provided or alternatively the four-electrode valve may be caused to maintain the high frequency circuit in oscillation by means of a reaction coil included in its anode circuit.

It will be seen that the present invention possesses the two principal advantages of 60 supersonic heterodyne receivers, namely, that 65 amplification may be effected at a lower fre-

quency than that of the received signals, and one which does not require to be altered with the wave length of the said received signals. In the present invention, however, the incoming signals modulate a generated intermediate frequency, and do not beat with a local oscillation to cause such a frequency, as in the supersonic heterodyne case. 70

In carrying out the invention, the amplitude of the local oscillations should be kept 75 comparatively small.

Although for the sake of illustration we have fully described the at present preferred form of our invention and the operation thereof we do not wish to limit ourselves 80 thereby except as marked out in the following claims:

1. A thermionic modulating device comprising a four electrode valve so constructed and arranged that under predetermined operating conditions an increase in inner grid potential causes a decrease in inner grid current, an oscillatory input circuit connected between the outer grid and cathode of said valve, an oscillatory output circuit tuned to the required frequency of oscillation of said valve and effectively connected between the inner grid thereof and the cathode, means for applying potential to the anode of said valve and to the inner grid thereof, and means for applying to the input circuit of said valve a modulating frequency whereby the amplitude of the oscillations in said output circuit is controlled in accordance with the oscillations in said first named oscillation circuit. 90

2. A thermionic modulating device comprising a four electrode valve so constructed and arranged that under predetermined operating conditions an increase in inner grid potential causes a decrease in inner grid current, an oscillatory input circuit connected between the outer grid and cathode of said valve, a circuit connected between the anode and cathode of said valve, means for coupling said last named circuit to said oscillatory circuit comprising an inductance coil in said last named circuit, an oscillatory output circuit tuned to the required frequency of oscillation of said valve connected between the inner grid thereof and the cathode, means for applying potential to the anode of said valve and to the inner grid thereof, and means for applying to the input circuit of said valve a modulating frequency, whereby the amplitude of the oscillations in said output circuit is controlled in accordance with the oscillations in said input circuit. 110

3. A thermionic modulating device comprising a four electrode valve having anode, cathode and two grid electrodes, said electrodes being so arranged that when a critical potential is applied to the outer grid an increase in inner grid potential will cause a decrease in inner grid current, an input oscillatory circuit including an inductance and a 125 130

variable capacity connected between the outer grid and the cathode of said valve, a reaction circuit including a source of potential, connected between the anode and the cathode of 5 said valve, an inductance in said reactance circuit coupled to the inductance in said input circuit, an oscillatory output circuit connected between the inner grid and the cathode of said valve, means for maintaining oscillations at a predetermined frequency therein including a capacity and an inductance and a source of potential, and means for varying the amplitude of the oscillations in said last 10 named oscillation circuit including means for applying to the input oscillatory circuit oscillations at a different frequency.

4. The method of signalling by means of

a four electrode valve having cathode, anode and inner and outer grid electrodes and oscillation circuits connected between said inner 20 and outer grids and said cathode which consists in, setting up oscillations at signal frequency in the circuit connected between said outer grid and said cathode, setting up oscillations at a different frequency in said circuit 25 coupled between said inner grid and said cathode, applying potential to said inner grid and said anode, and causing said first named oscillations to vary the amplitude of said last named oscillations in accordance with said 30 first named oscillations.
